UNITED STATES PATENT OFFICE.

THOMAS B. LEHON, OF CHICAGO, ILLINOIS, ASSIGNOR TO THE LEHON COMPANY, OF CHICAGO, ILLINOIS, A CORPORATION OF ILLINOIS.

ROOFING MATERIAL.

Application filed April 25, 1921. Serial No. 464,103.

To all whom it may concern:

Be it known that I, THOMAS B. LEHON, a citizen of the United States, and a resident of Chicago, in the county of Cook and 5 State of Illinois, have invented certain new and useful Improvements in Roofing Materials, of which the following is a specification, reference being had to the accompanying drawings.

10 My invention relates to improvements in that type of roofing that is made in sheet form and used either in long strips of the width of the original sheet or in small sheets or pieces cut into the shape and size of shingles and laid in overlapping relation in the way of an ordinary shingled roof. Such roofing material as now very generally made 15 comprises a base of fibrous material to which asphalt or similar plastic material is applied 20 while hot and forced into and upon the fabric base by suitable rollers, and having upon one surface of the sheet so formed a coating of comminuted or granular material, such as rock or slate, which is pressed upon the sheet 25 and adheres thereto. Other roofing material of this same general type is made by employing asbestos fibre and cement rolled into sheet shape while in a heated condition. I have found that by having imparted to such 30 roofing materials at intervals a series of corrugations that give to the material alternate channels and ridges a roofing is provided that is superior in many respects to the type of roofing referred to that is now in general 35 use, all as is hereinafter more particularly pointed out.

In the accompanying drawing,—

Fig. 1 is a perspective view of a roll of flexible roofing embodying my improvement; 40 Fig. 2 is a perspective view of a piece of such roofing and of a size designed to be used as a shingle;

Fig. 3 is an enlarged plan view of a portion of a shingle coated with granular material and provided with corrugations therein; and

Fig. 4 is an enlarged cross-sectional view through the shingle shown in Fig. 3.

Referring to the several figures of the 50 drawing, A represents a roll of flexible roofing in which the lines extending longitudinally thereof are intended to indicate the corrugations that are shown more clearly in Fig. 4, wherein is shown an enlarged sec-

tional view of a piece cut from such a roll 55 and designed to be used as a separate shingle. A complete shingle is shown in Fig. 2 and is designated as B, as are also the enlarged portions of such shingle that are shown in Figs. 3 and 4.

The shingle B, as shown, comprises a base a of fibrous material that, as usual, has been impregnated and coated with asphalt or similar plastic material while heated and upon the surface of which, while the said coating material was hot, has been pressed so as to adhere thereto a quantity of granulated material such as rock, slate, or other similar suitable substance. To this granular-coated roofing so formed, I impart a plurality of 60 corrugations, which is preferably done while the long sheet of material is in a warm and plastic condition and by passing such sheet between a pair of fluted rolls. Each of the ridges that is thus formed in the granular-coated or upper surface is indicated by c and the corresponding ridges that appear on the other surface are indicated by d. While any desired form of corrugation may be 65 thus impressed upon the material, I have 70 shown a form wherein each ridge has, as is clearly shown in Fig. 4, a short and comparatively steep incline on one of its sides while the other side is comparatively long and slopes very gradually toward and merges 75 into the short, steep side wall of the next ridge. So forming the two sides of each ridge, while still preserving suitable channels or gutters on the face of the material to 80 facilitate the carrying away of rain-water, 85 will present a more aesthetic appearance to the roof as a whole when viewed from a distance owing to the manner in which shadow effects are produced by such ridges, and hence I prefer such formation of the ridges. 90

A piece of roofing material corrugated as shown and described will, of course, be laid so that the corrugations extend at an angle to the eaves of a roof and will, therefore, provide a plurality of channels for conducting rain-water off of the roof, but another and very important object attained is the imparting of strength or rigidity to the material so that it better resists any tendency—especially when in the form of a shingle—to turn or warp, as frequently is the case with shingles of this type as heretofore constructed.

A roofing sheet or shingle comprising a uniformly corrugated layer of plastic material with a layer of grit embedded in and covering the layer of corrugated plastic material is not claimed broadly herein for the reason that such broad claims have been made in my copending application for patent on roofing material, Serial No. 559,327, filed May 8, 1922.

10 What I claim as my invention and desire to secure by Letters Patent, is—

1. A roofing member comprising fibrous and plastic materials associated together and having a series of corrugations formed in 15 its front and back surfaces.

2. A flexible roofing member coated on one of its faces with granular material, the body

of said member and the said coating thereon being corrugated.

3. Prepared roofing in sheet or shingle 20 form comprising layers composed of fibrous and plastic materials respectively and having a series of corrugations formed in both of the said layers.

4. Grit surfaced prepared roofing in sheet 25 or shingle form comprising, in combination, layers composed of fibrous and plastic materials respectively and having a series of corrugations formed in both of the said layers, and a layer of grit substantially uniformly embedded in and covering the layer 30 of corrugated plastic material.

THOMAS B. LEHON.
